Lake Grove, Oreg.

Filed Mar. 23, 1959, Ser. No. 55,125

Term of patent 14 years

(Cl. D9—2)

FIG.1

FIG.2

FIG.3

FIG. 4

Fig. 1 is a bottom plan view of a tooth brush, embodying my new design;

Fig. 2 is a fragmentary side elevational view thereof;

Fig. 3 is a fragmentary top plan view thereof; and

Fig. 4 is a fragmentary front end elevational view thereof.

The handle is shown broken away in Fig. 1 to indicate indeterminate length and is shown partly omitted in Figs. 2, 3 and 4 for convenience of illustration.

The dominant features of my design reside in the portions shown in full lines.

I claim:

The ornamental design for a tooth brush, as shown and described.
